UNITED STATES PATENT OFFICE.

EDWIN H. BELL, OF CHICAGO, ILLINOIS, ASSIGNOR TO THE RAILROAD SUPPLY COMPANY, OF CHICAGO, ILLINOIS, A CORPORATION OF ILLINOIS.

PROCESS OF MANUFACTURING TIE-PLATES.

No. 879,238.

Specification of Letters Patent.

Patented Feb. 18, 1908.

Application filed January 8, 1907. Serial No. 361,314.

To all whom it may concern:

Be it known that I, EDWIN H. BELL, a citizen of the United States, residing at Chicago, county of Cook, State of Illinois, have invented a certain new and useful Improvement in Processes of Manufacturing Tie-Plates, and declare the following to be a full, clear, and exact description of the same, such as will enable others skilled in the art to which it pertains to make and use the same, reference being had to the accompanying drawings, which form a part of this specification.

My invention relates in general to railroad track fastenings, and more particularly to a process of manufacturing tie plates.

It is customary to interpose metallic plates between railroad rails and the supporting ties in order to prevent the wearing away of the ties by the rails, and in order to more firmly secure the rails to the ties and thereby prevent both longitudinal creeping and lateral spreading of the rails with respect to the ties.

It is desirable that tie plates should have ribs or flanges on their under surfaces to prevent movement of the plates upon the ties, and should also have shoulders on their upper surfaces to prevent spreading of the rails. In order that tie plates may be as light as possible, and at the same time possess the requisite strength they may be advantageously provided with longitudinal grooves in their upper surfaces.

The primary object of my invention is to provide an improved process for economically and efficiently manufacturing tie plates having flanges on their under-surfaces to engage the ties and having shoulders on their upper surfaces to prevent the spreading of the rails, and also having grooves in their upper surfaces alining with the flanges.

My improved process may be generally described as consisting in passing a bar of metal successively between pairs of rolls having ribs and grooves on their peripheries, thereby step by step converting the bar into a continuous blank having longitudinal flanges on one surface and alining grooves on its other surfaces, then passing the blank between a pair of rolls, one of which completes the formation of the longitudinal flanges, while the other is provided with transverse grooves between longitudinal ribs on its periphery spaced apart distances cor-

responding to the desired length of the tie plates, thereby forming shoulders on the plates intermediate of the grooves, and finally cutting the continuous blank into sections to form tie plates.

My invention will be more fully described hereinafter with reference to the accompanying drawings illustrating the several steps comprising my process and in which

Figure 1 is an end view of a billet of metal; Fig. 2 elevational views of portions of the peripheries of a pair of rolls between which the billet is shown in section; Fig. 3 a view similar to Fig. 2 showing a pair of rolls between which the billet is subsequently passed; Fig. 4 a sectional view of the billet after having passed between successive pairs of rolls; Fig. 5 a cross-sectional view of the billet at a later period in its treatment; Fig. 6 a sectional view of the billet prior to being passed through the last pair of rolls; Fig. 7 a longitudinal sectional view through the blank into which the billet has been converted showing the adjacent peripheries of the last pair of rolls which form the shoulders on the blank; Fig. 8 an elevational view of the last pair of rolls which form the shoulders on the blank, the blank being shown in section; and Fig. 9 an end elevation of a completed tie plate.

Similar reference characters are used to designate similar parts in the several figures of the drawing.

Reference character A designates a billet of metal which is to be converted by my improved process into tie plates.

Reference characters B' and C' designate the rolls in a pair between which the billet is passed, the roll B' having ribs b', b' on its periphery, while the roll C' has three ribs c' on its periphery, the coöperating ribs on the rolls serving to impart to the billet a cross-section such as indicated at A'. The rolls have side flanges b and c respectively which prevent the billet from spreading laterally and consequently result in its being extended longitudinally.

In Fig. 3 I have illustrated at A² the cross-section of the billet after having been passed through successive pairs of rolls, in such figure the billet being shown as between rolls B² and C², the former having three grooves b² and the latter three ribs c² on its periphery.

In Fig. 4 I have illustrated at A³ the cross-

section of the billet after having passed between additional pairs of rolls while in Fig. 5 I have shown at A⁴ the cross-section of the billet at a later stage in its treatment.

- 5 In Fig. 6 A⁵ indicates the cross-section of a blank into which the billet has been converted by being passed between the successive pairs of rolls. The rolls in the successive bars are arranged nearer together so that the 10 billet will be gradually flattened, and the peripheries of the rolls in the successive pairs are such as to gradually impart to the billet longitudinal grooves on one surface and longitudinal flanges on its other surface. 15 The successive pairs of rolls through which the billet has passed in being converted into the blank shown in cross-section in Fig. 6, form longitudinal raised portions between the grooves on the upper surface of the blank, 20 such raised portions being formed to afford the metal to be longitudinally displaced in the subsequent step by which the shoulders are formed.

After the billet has been converted into a 25 blank having a cross-section such as indicated in Fig. 6, the blank is passed between a final pair of rolls indicated in Figs. 7 and 8 by means of which raised metal intermediate of the grooves is longitudinally displaced to 30 form transverse shoulders intermediate of the grooves at distances apart corresponding to the desired length of the tie plates.

Referring more particularly to Figs. 7 and 8 reference character A⁷ indicates the blank 35 after passing between the last pair of rolls B⁷ and C⁷.

a⁷ indicates the shoulders formed on one surface of the blank by the grooves b⁷. The grooves b⁷ are formed intermediate of the 40 four longitudinal ribs b⁸ on the periphery of the roll B⁷ which completes the formation of the longitudinal grooves a⁵ in the upper surface of the blank.

c⁷, c⁷ designate longitudinal grooves in the 45 periphery of the roller C⁷ which complete the formation of the flanges on the under-surface of the blank, the outer grooves being of a greater depth than the intermediate ones, thereby forming the outer flanges D, D of 50 greater depth than the intermediate flanges d, d on the under-surface of the blank. After the continuous blank has passed between the rolls B⁷ and C⁷ it is cut into lengths to form the tie plates, having a cross-section, such as 55 indicated in Fig. 9. The continuous blank is cut transversely adjacent each series of

shoulders so that the shoulders are located adjacent one end of the tie plate.

From the foregoing description it will be observed that I have invented an improved process for economically and efficiently converting a billet of metal into tie plates, having longitudinal flanges for engaging the ties on their under-surfaces, having longitudinal grooves in their upper surfaces alining with the flanges, and having shoulders intermediate of the grooves for preventing the lateral spreading of the rails.

Having now fully described my invention, what I claim as new and desire to secure by Letters Patent is:

1. The process of manufacturing a tie plate blank which consists in first rolling a billet of metal into a continuous strip having longitudinal grooves in one surface and longitudinal ribs on the other surface opposite the grooves, and then rolling the strip so as to displace the metal intermediate the grooves sufficiently longitudinally to produce transverse shoulders on the upper surface of said strip at certain distances apart.

2. The process of manufacturing a tie plate blank, which consists in first rolling a billet of metal into a continuous blank having a plain under surface provided with longitudinal ribs and an upper surface divided into a plurality of longitudinal bead-like sections arranged opposite the spaces between the ribs on the other surface and forming grooves above said ribs and then passing said strip through rolls arranged to displace longitudinally enough of the material of said bead-like sections to produce transverse shoulders on said strip arranged at certain distances apart.

3. The process of manufacturing a tie plate blank, which consists in first rolling a billet of metal into a continuous strip having longitudinal ribs on its under surface and an upper surface divided into a plurality of longitudinal bead-like sections, and then passing the strip through rolls arranged to displace a portion of the material of said bead-like sections longitudinally and to leave transverse shoulders projecting above said bead-like sections at certain distances apart.

In testimony whereof, I sign this specification in the presence of two witnesses.

EDWIN H. BELL.
